Primary Examiner—Theodore M. Shooman
Attorney, Agent, or Firm—Terry M. Gernstein**[57]****CLAIM**

The ornamental design for a toilet cover and seat position signal combined with a sensor, as shown and described.

DESCRIPTION

FIG. 1 is an exploded perspective view of the toilet cover and seat position signal combined with a sensor showing our new design;

FIG. 2 is a front elevational view thereof;

FIG. 3 is a rear elevational view thereof;

FIG. 4 is a side elevational view thereof;

FIG. 5 is a side elevational view thereof; and,

FIG. 6 is a top plan view thereof, the bottom view being a mirror image of the top view shown in FIG. 6.
